(57) **CLAIM**

The ornamental design of a whole body of car, as shown and described.

DESCRIPTION

FIG. 1 is a perspective view of a whole body of car showing the new design;

FIG. 2 is a front view thereof;

FIG. 3 is a rear view thereof;

FIG. 4 a left side view thereof;

FIG. 5 is a right side view thereof; and,

FIG. 6 is a top plan view thereof.

The design can be embodied with metal, glass, plastics, rubber, etc. This design of a car is characterized in that it has a hatchback style body, and it has beautiful and modern images due to harmony of its parts which are newly created.
